(57) **CLAIM**

The ornamental design for a power strip, as shown and described.

DESCRIPTION

FIG. 1 is a front, bottom, left side perspective view of a power strip according to the present disclosure;
FIG. 2 is a front, top, right side perspective view thereof;
FIG. 3 is a bottom perspective view thereof;
FIG. 4 is a front elevational view thereof;
FIG. 5 is a rear elevational view thereof;
FIG. 6 is a left-side elevational view thereof;
FIG. 7 is a right-side elevational view thereof;
FIG. 8 is a top plan view thereof; and,
FIG. 9 is a bottom plan view thereof.
The broken lines shown in the drawings depict portions of the power strip that form no part of the claimed design.
